COMBINED ELECTRICAL FUSE PULLER AND INSERTER

Douglas E. Maiden, 1206 78th St., Newport News, Va.,
and Wayland H. Dickerman, 5241 W. Fond Du Lac
Ave., Milwaukee, Wis.

Filed May 11, 1962, Ser. No. 70,082

Term of patent 14 years

(Cl. D54—13)

FIG. 1

FIG. 2

FIG. 3

FIG. 4

FIG. 1 is a full front elevational view of our new design of a combined electrical fuse puller and inserter;

FIG. 2 is a side elevational view of our new design;

FIG. 3 is a cross-sectional view on line 3—3 of FIG. 1; and

FIG. 4 is a cross-sectional view on the line 4—4 of FIG. 1.

We claim:

The ornamental design for a combined electrical fuse puller and inserter, as shown.
